UNITED STATES PATENT OFFICE.

MILTON J. MATTHEWS, OF DETROIT, MICHIGAN.

TIME-CONTROLLED MECHANISM.

1,240,749.

Specification of Letters Patent. Patented Sept. 18, 1917.

Application filed March 12, 1917. Serial No. 154,203.

To all whom it may concern:

Be it known that I, MILTON J. MATTHEWS, a citizen of the United States, residing at Detroit, in the county of Wayne and State 5 of Michigan, have invented new and useful Improvements in Time-Controlled Mechanism, of which the following is a specification.

My present invention pertains to time- 10 controlled mechanism; and it consists in the peculiar and advantageous mechanism, hereinafter described and claimed, constructed with a view to bringing about at a pre-determined time the supply of fuel to a furnace, the shaking of the grate of the furnace, the opening of the bottom draft door, and the closing of the check-draft door.

In the accompanying drawings, which are hereby made a part hereof:

20 Figure 1 is a view diagrammatic in character and illustrating the arrangement of my novel mechanism relative to a furnace.

Fig. 2 is an enlarged elevation, taken at right angles to Fig. 1 and showing the main shaft of the mechanism and its appurtenances together with an alarm clock or other suitable clock and the connection intermediate the same and the main shaft for releasing the latter at a pre-determined time.

30 Fig. 3 is a detail section showing the arrangement of the pawl-lever relative to the ratchet disk on the main shaft.

Similar numerals of reference designate corresponding parts in all of the views of 35 the drawings.

The furnace 1, illustrated in Fig. 1, is shown as equipped with a coal chute 2, normally closed at its outer end by a door 3, and provided with a vertically-movable cut-off door 4, the latter being located adjacent to the lower end of the chute that communicates with the fire box of the furnace. The furnace is also shown as provided with the conventional draft door 5, lever 6 adapted 40 when oscillated toward and away from the furnace casing to actuate a grate (not shown), and a check-draft door 7. While these elements 5, 6 and 7 are preferably of conventional type, I do not desire to be 45 understood as confining myself to the same, it being within the scope of my invention to employ corresponding elements of any description compatible with the purpose of my invention, and to transmit motion from 50

the oscillatory lever 6 to a grate to actuate 55 the latter, in any approved manner.

Arranged in fixed relation to the furnace and spaced from the front thereof is a frame embodying two standards 9 and a clock-saddle 16, and journaled in the said standards 9 is the main shaft 8 of my novel mechanism; said shaft having one of its ends of angular formation, as shown, for the application of a key (not shown) through the medium of which the shaft is turned to 60 raise the weight or wind the spring employed to operate the mechanism, a weight being preferably employed for the purpose, and it being deemed unnecessary to illustrate a spring which is recognized as a full 65 mechanical equivalent of a weight. At 10 the shaft 8 is provided with a pulley, and at 11 with a crank, the latter being connected through a pitman, Fig. 1, with the grate-actuating lever 6. It will also be noted by 70 reference to Fig. 2 that the shaft 8 is provided with a ratchet-disk 13, and an aperture 12, the latter being for the connection of a certain cable 26, and the portion of the shaft adjacent to the aperture 12 being circumferentially grooved as shown to facilitate 75 the winding of the said cable.

The clock-saddle 16 is provided with a stop 23, and the clock which is shown as secured in the said saddle and which may be 80 of the alarm type or any other type that is provided with an arbor adapted to be rotated at a pre-determined time for which the clock is set, is provided on the said arbor with a disk 18, fixed to the arbor and 85 provided with a plurality of apertures 19. In one of the said apertures is removably arranged the angularly-disposed upper end of a link 20, the lower end of which is connected to one arm of a vertically-swinging 90 lever 21, mounted on the saddle 16. The other arm of the said lever 21 is connected through a rod 22 with a pawl lever 14 mounted on one of the standards 9 and normally held by a retractile spring 15 in yielding 95 engagement with the ratchet disk 13.

Connected to and designed to be wound on the pulley 10 is a cable 24 that is passed over overhead sheaves as shown in Fig. 1 and carries a weight 25. The cable 26, here- 100 before referred to, is likewise carried over overhead sheaves, and its end remote from the shaft 8 is connected to the cut-off door 105

4. A third cable 28 is passed over overhead sheaves and is connected at its ends to the draft door 5 and the check-draft door 7. This latter cable 28 is connected 5 through a short cable 27 with the cable 26.

In the practical use of my improved mechanism, the clock is wound and set for the predetermined time at which it is desired to have the mechanism operate, and 10 the shaft 8 is rotated to wind the cable 24 on the drum, and to also wind the cable 26, the latter winding being designed to leave the cable 26 in a taut state, with the door 4 in a closed position, and the door 5 15 closed and the door 7 in open position.

Also, the chute 2 is charged with coal and the door 3 is closed, and the link 20 is connected to the disk 18 so as to establish connection between the said disk and the pawl 20 lever 14 which normally engages the ratchet disk 13 and thereby prevents casual rotation 25 of the main shaft 8 under the gravitation of the weight.

With the mechanism set as described in 25 the foregoing, it will be manifest that at the time for which the mechanism is set, the disk 18 will be rotated and through the link 20 will raise one arm of the lever 21 against the stop 23 and will also through 30 the said lever and the link 22 disengage the pawl-lever 14 from the ratchet disk 13, whereupon the gravitation of the weight 25 will rotate the shaft 8 and wind the cable 26 on said shaft, with the result that the 35 door 4 will be opened to precipitate the coal on the fire in the furnace, and the draft door 5 will also be opened while the check-draft door 7 will be permitted to gravitate to a closed position. Also by reason of the rotation 40 of the shaft 8, the grate lever 6 will be oscillated and the grate (not shown) actuated. Thus without the presence of an attendant, the furnace will be made to raise the temperature of the air in a dwelling or 45 other building, at a time when it is desired for the dwelling or other building to become warmer, as in the morning.

I have entered into a detailed description 50 of the construction and relative arrangement of the parts comprised in the present and preferred embodiment of my invention in order to impart a full, clear and exact understanding of the said embodiment. I do not desire, however, to be understood as

confining myself to the said specific construction and relative arrangement of parts, as in the future practice of the invention such changes or modifications may be made as fairly fall within the scope of my appended claims.

Having described my invention, what I claim and desire to secure by Letters-Patent, is:

1. In means for the purpose described, the combination of a gravitating draft door of 65 a furnace, a gravitating check-draft door also complementary to a furnace, a gravitating door for controlling the supply of fuel to a furnace, sheaves located in a horizontal plane above the check-draft door, a cable 70 passed over said sheaves and extending between and connected to the gravitating draft door and the gravitating check-draft door, a third sheave, a cable connected to the fuel-controlling door and passed over the 75 last-named sheave, a branch cable connecting the said cables at a point below the sheaves, and means for taking up the cable that is passed over the last-named sheave.

2. In means for the purpose described, the combination of a grate-actuating lever, supporting means, a shaft journaled in the latter means and having a ratchet disk, a crank on said shaft, a pitman intermediate said crank and the grate-actuating lever, means 80 connected with the shaft for rotating the same when it is released, a pawl lever mounted on the supporting means and yieldingly maintained in engagement with the ratchet disk, a clock mounted on the supporting means 85 and having a disk adapted to be revolved at a predetermined time and also having apertures in said disk off the center thereof, a vertically-swinging lever on the supporting means, a connection between one arm of said lever and the pawl lever, and a link connected to the other arm of the vertically-swinging lever and having an angularly disposed end portion adapted for removable arrangement in one of the apertures of the disk.

In testimony whereof I have hereunto set my hand in presence of two subscribing witnesses.

MILTON J. MATTHEWS.
